UNITED STATES PATENT OFFICE.

WILLIAM T. BEATTY, OF FLOSSMOOR, FRANK S. DAVIS, OF HOMewood, AND FRED D. WILSON, OF HARVEY, ILLINOIS; SAID DAVIS AND SAID WILSON ASSIGNEES TO AUSTIN MANUFACTURING CO., OF CHICAGO, ILLINOIS, A CORPORATION OF ILLINOIS.

DOUBLE CONTROL FOR ROAD-ROLLER SCRAPER ATTACHMENTS.

Application filed October 24, 1923. Serial No. 670,494.

To all whom it may concern:

Be it known that we, WILLIAM T. BEATTY, FRANK S. DAVIS, and FRED D. WILSON, citizens of the United States, residing, respectively, at Flossmoor, Homewood, and Harvey, in the county of Cook and State of Illinois, have invented a certain new and useful Improvement in Double Controls for Road-Roller Scraper Attachments, of which the following is a specification.

This invention relates to road roller maintainers of the general type shown in our earlier application, Serial Number 610,345, filed January 2, 1923, in which a road rolling machine is equipped with a transverse maintainer or scraper capable of working upon the surface of the road simultaneously with the rolling thereof.

The principal object of this invention is to provide a single mechanism under the control of an operator riding upon the roller which is not only capable as in said prior application of raising and lowering the entire maintainer as a unit with reference to the roller and the road over which the machine travels; but which is capable of selective manipulation to independently control the height of at least one end and preferably both ends of the maintainer blade.

The invention consists in mechanism capable of attaining the foregoing and other objects; which can be easily and cheaply made; which is satisfactory in use and is not readily liable to get out of order. More particularly, the invention consists in various features and details of construction which will be hereinafter more fully set forth in the specification and claims.

Referring to the drawings in which like numerals designate the same parts throughout the several views:

Figure 1 is a side elevation of a road roller maintainer machine equipped with the mechanism of this invention in its preferred form.

Figure 2 is a view of the opposite side of Figure 1, showing the extended side of the blade. (See arrow 2, Fig. 3.)

Figure 3 is a plan view of the mechanism of Figure 1.

Figure 4 is a front view of the machine taken on the irregular line 4-4 of Figure 3.

Figure 5 is a sectional, detail view on the line 5-5 of Figure 1.

Figure 6 is a detail of the gearing used in the maintainer elevator mechanism, appearing in the upper left hand portion of Figure 1.

Figure 7 is a detail plan view on the line 7-7 of Figure 1 of a form of mechanism by which the operator may selectively elevate either the entire maintainer blade or one end thereof.

Figure 8 is a corresponding plan view of an alternative construction by which the operator may selectively manipulate one mechanism to elevate or depress the entire maintainer mechanism or either selected end thereof.

The drawings show a road roller engine frame 10, carried on rear rollers 12 and a front roller mechanism 14, in the particular case here illustrated, two aligned rollers mounted on the same axle 16 inside a yoke 18 journaled on a vertical shaft 20 entering the arched member 22 on the frame 10. An operator occupying a seat 24 at the rear of the machine can turn the vertical shaft 20 and consequently the roller 14 by properly manipulating an adjacent hand wheel 26 on a shaft 28 operatively connected through gearing 30-32 to a segmental gear 34 secured to shaft 20 by any suitable means as key 36.

The conventional roller mechanism just described is equipped with a U-shaped maintainer frame more fully described and claimed in said prior application comprising parallel side members 38 and 40 lying on opposite sides of roller 14 and a transverse cutting or maintainer blade 42 capable of angular adjustment between the full line and dotted line positions of Figure 3 through the agency of adjusting bolts 44 cooperating holes 46 therefor and removable braces 48. This frame is, as in said prior application, secured about the roller 14 and on movement of the roller pushed or pulled along the road through the agency of diagonal brace members 50 and 52 adjustably attached to the body 10 of the roller through any suitable means as, for instance, set screws or bolts 56 selectively insertable in holes 58 or 60, as the case may be, provided for them in the re-

- spective members 52 and 50. As fully set forth in said prior application, the further end of each diagonal brace rod 50 and 52 is engaged by a downwardly movable rod 5 62 provided with a cushion spring mechanism 64 with the result that each adjacent side member of the U-shaped maintainer frame and consequently the blade 42 is pressed firmly upon the ground. The mechanism 10 for exerting this pressing action on these rods 62 and conversely for elevating them constituting a principal feature of this invention will now be described.
- The upper end of the rod 62 on the left 15 hand side of the machine as viewed in Figure 4 is pivotally attached at 66 to a lever arm 68 carried by a shaft 70, journaled in a bracket 71 provided for it, extending across the machine.
- 20 The right hand end of the bracket 71 as viewed in Figure 4 has rigidly secured to it by any suitable means, as, for instance, bolts 72, a gear housing 74 carrying two parallel segmental gears 76 and 78, the former rigidly secured to shaft 70 by any suitable means as, for instance, a key 80, the latter freely rotatable on said shaft 70. Journaled on the right hand end of shaft 70, as viewed in Figure 4, is a lever arm 82, 25 resembling in outward appearance lever 68, heretofore referred to, and detachably pivotally connected to the right hand rod 62 by any suitable means as a pin 84. The hub 86 of lever 82 and the hub 88 of segmental gear 78 are detachably connected together around an intervening portion 90 of the gear housing wall by means of suitably disposed lugs 92 and 94 and interconnecting bolt 96 (see Figure 5).
- 30 Extending through the gear housing 74 and suitably journaled in its opposite walls are parallel shafts 98 and 100 carrying, respectively, worms 102 and 104 meshing, respectively, with segmental gears 76 and 78.
- 35 In the specific form of the invention shown in Figure 7, in which the operator can selectively elevate or depress the entire maintainer or elevate or depress one end of the blade 42, in the particular case here illustrated, the right hand end as viewed in Figure 4, shaft 100 extends back to a point in proximity to the driver's seat 24 and there carries a single wheel 106. Slidably mounted upon this shaft 100 and readily manipulatable by hand lever 108 adjacent to the driver's seat is a connecting sleeve 110 attached to a gear 112 mounted for limited reciprocation along shaft 100 but prevented from rotation thereon by any suitable means, as 40 for instance, a spline connection 114. This gear 112 meshes with corresponding gear 116 rigid on shaft 98 and the limits of movement along the spline connection 114 are such that the operator can by properly manipulating handle 108 cause the gears 45 112 and 116 to mesh as shown in Figure 7, or can move gear 112 along shaft 100 until it is entirely out of mesh with gear 116. When the gears are in mesh as shown in Figure 7, rotation of hand wheel 106 will 50 cause both segmental gears 76 and 78 to move in unison and will consequently simultaneously elevate or depress rods 62 and consequently the entire maintainer mechanism. When gear 112 is out of mesh 55 with gear 116, the friction in worm 102 locks shaft 98 and consequently that part of the maintainer mechanism attached thereto; while rotation of shaft 100 manipulates segmental gear 78 to, at the will of the operator, raise or lower the right hand end of the maintainer blade 42 as viewed in Figure 4.
- 55 In the alternative construction, shown in Figure 8, shaft 98 is according to the drawings equipped with a slightly wider gear 120, replacing gear 116. Shaft 100 as before extends to the driver's seat 24 and is there equipped with a hand wheel 106. The mechanism 110—112 of Figure 7 is removed 60 and in this construction replaced by a longitudinally reciprocable sleeve 124 carrying rigid thereon near hand wheel 106 another hand wheel 126. Rigidly secured to the opposite end of this member 124 by any suitable means as bolt or screw 128 is a clutch member 130 provided with clutch teeth 132 interfitting with other clutch teeth 134 on another clutch member 136 rigidly secured to shaft 100 by any suitable means 65 as, for instance, a pin 138. Rigid on clutch member 130 is a gear 140 meshing with gear 120. Wheel 128 and parts 124—130 and gear 140 are slidable lengthwise of shaft 100 between the position shown in Figure 8 70 and a position to the left thereof in which clutch teeth 132 interfit with clutch teeth 134 and thus lock these parts on shaft 100.
- 75 When the parts are in the position shown in Figure 8 and the operator manipulates hand wheel 106, he causes shaft 100 to rock segmental gear 78 to thus manipulate up or down as the case may be the right hand end of the maintainer as viewed in Figure 4. When, under the same conditions, the operator rotates wheel 126, he causes gear 140 to rotate gear 120 and consequently through the parts attached thereto rock segmental gear 76 to raise or lower, as the case may be, the left hand end of the maintainer 80 as viewed in Figure 4. When the operator takes hold of the handle 126 and shoves the gear 140 to the left, as viewed in Figure 8, until clutch teeth 132 and 134 intermesh, then manipulation of either hand wheel 106 85 or 126 will cause gears 140 and 120 to rotate in unison thus moving segmental gears 76 and 78 in unison thus raising or lowering as the case may be the entire maintainer.
- 90 From the foregoing, it will be seen that 95

by installing the mechanism of Figure 7, the operator on seat 24 can by the manipulation of a single hand wheel and shaft selectively raise or lower the entire maintainer or raise or lower a given predetermined end thereof; and that, by the use of the mechanism of Figure 8 still carried by a single shaft extending forward from the operator's position, the operator can at will 10 by rotating that one shaft or mechanism journaled thereon raise or lower the entire maintainer or raise or lower either end thereof. By the use of these simple, readily installed mechanisms, the operator on seat 15 24 has absolute control of the maintainer blade 42 at the front of the machine to make the road or other surface worked upon as desired.

The maintainer mechanism described is 20 held against lateral movement with reference to the roller frame 10 by a transverse rod 140 and rattling of the parts is prevented by a cushion spring 142 adjustably held in place by any suitable means as, for 25 instance, lock nut mechanism 144.

Manipulation of the maintainer frame as described is materially facilitated by the use of oppositely disposed cushion springs 150 and 152 attached at their lower ends to 30 suitable points on the maintainer frames and at their upper ends to short lever arms 154 or 156, as the case may be, extending on the opposite side of shaft 70 from the 35 respective lever arms 68 and 82.

Having thus described our invention, what we claim as new and desire to secure by Letters Patent is:

1. In mechanism of the class described, a 40 road roller, a maintainer at one end of the roller, force transmitting connections between the maintainer and roller, and adjustable means, operable when in one adjustment, to impart positions to the maintainer relative to the roller different from any positions imparted thereto relative to the roller, when said means is operated in another adjustment.

2. In mechanism of the class described, a 50 road roller, a maintainer at one end of the roller, force transmitting connections between the maintainer and roller, and adjustable means operable when in one adjustment to shift the vertical position of the entire maintainer and when in another 55 adjustment to shift the vertical position of one end of the maintainer only.

3. In mechanism of the class described, a 60 road roller carrying an operator's station, a maintainer at one end of the roller, force transmitting connections between the maintainer and roller, and means, adjustable and operable from said station, effective when operated in one adjustment to impart positions to the maintainer relative to the roller 65 different from any positions imparted there-

to relative to the roller, when said means is operated in another adjustment.

4. In mechanism of the class described, a 70 road roller carrying an operator's station, a maintainer at one end of the roller, force transmitting connections between the maintainer and roller, and means, adjustable and operable from said station, effective when operated in one adjustment to shift the vertical position of the entire maintainer and when operated in another adjustment to shift the vertical position of one end of the maintainer only. 75

5. In mechanism of the class described, a 80 road roller carrying an operator's station, a maintainer at an end of the roller, force transmitting connections between the roller and maintainer, and means selectively operable from said station either to shift the vertical position of the entire maintainer or 85 to shift the vertical position of an end thereof individually.

6. In mechanism of the class described, a 90 road roller carrying an operator's station, a maintainer at an end of the roller, force transmitting connections between the roller and maintainer, and means, adjustable and operable from said station, effective, when operated in one adjustment, to shift the vertical position of the entire maintainer 95 and when operated in other adjustments to respectively shift the vertical positions of the ends of the maintainer only.

7. In mechanism of the class described, a 100 three wheel road roller carrying an operator's station, a U-shaped maintainer mechanism embracing a front wheel of the roller, force transmitting connections between the maintainer and roller, and means, adjustable and operable from said station, effective, when operated in one adjustment to elevate and depress the entire maintainer and when operated in another adjustment to elevate and depress one end of the maintainer only. 105

8. In mechanism of the class described, a 110 three wheel road roller carrying an operator's station, a U-shaped maintainer mechanism embracing a front wheel of the roller, force transmitting connections between the maintainer and roller, and means adjustable and operable from said station, effective, when operated in one adjustment to elevate and depress the entire maintainer and when operated in other adjustments to respectively elevate and depress the ends of the maintainer only. 115

9. In mechanism of the class described, a 120 road roller, a maintainer at one end of the roller, force transmitting members attached 125 to the maintainer and pivotally connected to the roller, and adjustable means operable in one adjustment through said force transmitting members to elevate and depress the entire maintainer and in another adjustment 130

through one of said members to elevate and depress one end of the maintainer only.

10. In mechanism of the class described, a road roller, a maintainer, force transmitting members attached to the maintainer and pivoted to the roller, said members operating during movement of the roller in one direction to push the maintainer, and adjustable means operable in one adjustment through the force transmitting members to elevate and depress the entire maintainer and in another adjustment through one of said members to elevate and depress one end of the maintainer only.

11. In mechanism of the class described, a road roller, a maintainer operatively connected to the roller to be pushed by the latter, and adjustable means operable in one adjustment to elevate and depress the entire maintainer and in another adjustment to elevate and depress one end of the maintainer only.

12. In mechanism of the class described, a maintainer tool, independently operable shifting mechanisms effective to elevate and depress different ends of the maintainer respectively, and means for connecting said mechanisms for unitary operation.

13. In mechanism of the class described, a maintainer tool, a pair of shifting mechanisms effective to elevate and depress different ends of the maintainer respectively, a shaft for operating one of said mechanisms and extending from the latter to a relatively distant point, and means operable from the distant end of the shaft to connect the latter with the other shifting mechanism.

14. In mechanism of the class described, a maintainer tool, independently operable shifting mechanisms effective to elevate and depress different ends of the maintainer respectively, a shaft for operating one of said mechanisms and extending from the latter to a relatively distant point, and means selectively operable from the distant end to the shaft to independently actuate the other shifting mechanism and to connect said shaft with said last named shifting mechanism.

15. In mechanism of the class described, a maintainer tool, independently operable shifting mechanisms effective to elevate and depress different ends of the maintainer respectively, a shaft for operating one of said mechanisms and extending from the latter to a relatively distant point, and means on said shaft selectively operable from the distant end thereof to independently actuate the other shifting mechanism and to connect said shaft with said last named mechanism.

16. In mechanism of the class described, a maintainer tool, independently operable shifting mechanisms effective to elevate and depress different ends of the maintainer respectively, a shaft for operating one of said mechanisms and extending from the latter to a relatively distant point, means rotatable and adjustable on the shaft from the distant end thereof, said means being effective, when rotated in one adjustment, to independently actuate the other mechanism and serving, when in another adjustment, to connect said shaft with the last named shifting mechanism.

17. In mechanism of the class described, a maintainer tool, independently operable shifting mechanisms effective to elevate and depress different ends of the maintainer respectively, a shaft for operating one of said mechanisms and extending from the latter to a relatively distant point, and a gear and clutch device rotatable and adjustable on the shaft from the distant end thereof, said device being effective, when rotated in one adjustment, to independently operate the other shifting mechanism and serving, when in another adjustment, to connect said shaft with the last named shifting mechanism.

18. In mechanism of the class described, in combination with two parallel shafts and mechanism to be operated by each, a gear fixed on one shaft, another gear meshing with the first rotatable on and slidable along the second shaft, means for independently rotating said second gear and for so reciprocating it, a separable clutch device having one part rigid with the second gear and its other part rigid on said shaft, and means for rotating the second shaft.

19. In mechanism of the class described, in combination with a road roller frame, a maintainer pushed thereby, a diagonal connecting rod 140 between the two frames and a cushion spring 142 on said rod as described.

20. In mechanism of the class described, in combination with a traveling roller, a maintainer to be controlled thereby, a pair of pivoted lever arms (68 and 72) equipped with mechanism for pressing the maintainer on the ground, means for so actuating said lever arms, an oppositely extending arm projecting from each of said first arms and a spring (150 or 152) connecting said arm and the maintainer.

In witness whereof, we have hereunto subscribed our names.

WILLIAM T. BEATTY.
FRANK S. DAVIS.
FRED D. WILSON.
